UNITED STATES PATENT OFFICE.

MARTIN AUGUST SEAHOLM, OF CHICAGO, ILLINOIS.

PUMP AND MOTOR.

Application filed December 27, 1927. Serial No. 242,634.

My invention relates to an engine of the rotary piston type which may be used either as a pumping engine or a motor, and is reversible in direction of rotation. The present application relates more particularly to an invention embodied in a construction illustrated and described as a modified form of the invention of my pending application for patent filed December 9, 1926, Serial No. 153,524, and the present application which may be regarded as in part a continuation of said former application, is intended to specifically cover a pumping engine or motor in which a pair of sleeves, severally connected to vane members, are arranged to cooperate with a single diametrically-slotted rotor member. The principal advantage which it is the object of my invention to attain is a reduction in the vibration of the engine which is due to acceleration and retardation of the sleeve member employed in pumps having but one such member.

In the drawings accompanying this specification I have illustrated my invention both in the best form known to me and a modified form. Figure 1 of the drawings shows in elevation the parts of the engine as seen beyond a plane indicated by the dotted line 1-1 of Fig. 2, with the cap plate shown at the left of said Fig. 2 removed, and viewing the parts from left to right, as indicated by the arrow;

Fig. 2 is a central vertical section of the engine, the rotor being shown partly in elevation and partly broken away to better show its construction and the arrangement of the vane members;

Fig. 3 is a face view of the right end cap plate as indicated by the dotted line 3-3 of Fig. 2;

Fig. 4 is a face view of the vane members, detached;

Fig. 5 is a view of a modified form of my invention corresponding to Fig. 1; and

Fig. 6 is a central vertical section of said modified form, corresponding in general to Fig. 2.

Like reference letters indicate like parts in all the figures of the drawings.

Describing first the preferred form of my invention, the casing of the engine includes a central annular body member 1, formed with a base 1^a by means of which it is supported, and having parallel ground end faces to provide a tight joint with the correspondingly finished faces of a left end cap plate 2 and

right end cap plate 3. The body member 1 is formed with a pair of oppositely arranged flow passages 4-4^a extending horizontally near each other from end to end, one on each side of the center of the machine and near its top. The passages 4 and 4^a communicate respectively with openings in bosses 5-5^a which provide inlet and outlet flow connections with such passages.

The cap plates 2 and 3 are each formed with recesses in communication with the flow passages 4 and 4^a of the body member, the form and arrangement of the recesses being illustrated in Fig. 3. Each recess consists of a top portion 6 and an arcuate lower and inner portion 6^a which is concentric with the axis of a rotor member later to be described and provides a port opening into the working chamber of the engine. The ends of the ports 6^a in each cap plate lie diametrically opposite the axis of the rotor.

Rotatably seated within the bearing formed by the inner face of the annular body member are two sleeves 7 and 8 which make sliding contact with each other and with the inner faces of the cap plates 2 and 3, respectively. For lightness of construction these sleeves may be formed with central peripheral channels, as illustrated.

Within the sleeves 7 and 8 is arranged the rotor member before referred to, marked 9, which is arranged eccentrically of such sleeves and in sliding contact therewith along a line midway between the passages 6 and 6^a on opposite sides of the center of the engine. The rotor is secured in the present instance by a cross-pin 10, to a shaft 10^a which is journaled in the end plates of the engine and may be provided with glands to form a sealed bearing as shown.

The rotor member is formed with two diametrically opposite radial slots, within which are arranged two pairs of vane members, one pair associated with the sleeve member 7 and the other pair with the sleeve member 8. One vane, marked 11, of the pair of vanes associated with the sleeve 7 is pivoted to such sleeve through a pivot portion 11^a which permits a limited swinging movement of the vane, while the other vane, marked 12, is not so connected and is free to slidably follow the inner face of the sleeve. The other pair of vanes are similarly arranged, excepting that the pivotal end 13^a of the vane 13 is pivoted to the sleeve 8 at a point diametri-

cally opposite the pivot 11^a, and the vane 14 is on the opposite side of the rotor from the vane 12. The inner sides of the two sets of vane members slightly contact each other, and the outer sides make sliding contact with the inner faces of the cap plates 2 and 3, severally. Preferably the two radial slots in which the vanes work communicate with each other through orifices 10^b extending through the central portion of the rotor and the shaft 10.

The modified form of my invention illustrated in Figs. 5 and 6 is the same as that described in my said pending application, and differs from that already described in that the rotor is formed in two parts, marked 14 and 15, rigidly secured together by bolts and formed respectively with disk-shaped extensions 16 and 17 integral with journal portions 18 and 19, respectively, said extensions and journal portion being rotatably mounted in seats formed in the cover plates 2^a and 3^a. The rotor sections are formed with diametrical slots which when the sections are secured together form a single continuous slot extending through the rotor. The vane members are longer in diametrical dimensions than the vanes of the preferred form of my invention illustrated in Figs. 1 to 4, and if desired springs 20 may be interposed between the members of each pair, as illustrated, to maintain contact of the free vane with the inner wall of its associated sleeve. In practice, however, the centrifugal force of such member has been found to effect this result and the springs may therefore be omitted.

Like the engine described in my aforesaid pending application, my present engine is entirely symmetrical in construction and reversible with respect to its flow connections and direction of rotation, and may be operated either as a pump or blower, or as a motor. Assuming it to be operated as a blower (or compressor), and the shaft 18 to be positively driven in the direction indicated by the arrow upon Figs. 1 and 5, at a constant speed, the flow passage 4 will be the intake and the passage 4^a the outlet for air or other fluid acted upon. The space between the rotor and two sleeves 7 and 8 and the inner faces of the cap plates 2 and 3 intermediate the ends of the arcuate ports in such caps and below the horizontal diameter of the rotor constitutes a working chamber which the vanes on the side of the rotor leave as the vanes on the other side enter, so that the laterally adjacent vanes working in the slot on one or the other side of the rotor will at all times be drawing in the air into the cylinder on their rear sides through the ports 6^a in the cap plate 2 and flow passages leading from the boss 5, and forcing the air in front of them in such cylinder out through the op-

posite ports 6^a and flow passages leading through the boss 5^a. The laterally adjacent vanes 11 and 14 consequently function as one piston, and the vanes 12 and 13 as another, the pistons alternately traversing the working chamber in one direction.

It is obvious that while the rotor and sleeves 7 and 8 will always remain in contact at their line of contact at the top, the pivoted base 11^a of the vane 11 traveling in the circumference of the sleeve 7, will traverse a longer path than the end of the rotor slot in which such vane slides, which travels in the circumferential path of the face of the rotor, and that said sleeve, in making one complete revolution from the position shown in Fig. 1, will be accelerated uniformly throughout the first half of its revolution, and retarded uniformly throughout the remaining half. The sleeve 8 will in the same manner be accelerated during the period while the pivot 13^a of the vane 13 travels from a position at the highest point of its path to the lowermost position, be retarded during the remainder of its revolution, and since the pivotal connection 11^a and 13^a are 180° apart, it follows that one vane will be accelerating while the other vane is retarding. The inertia of one sleeve and connected vane will therefore balance the momentum of the other sleeve and vane, and all vibration from this source be eliminated. At the high speeds at which the engine is operated this is an important advantage, and greatly increases the smoothness of its running.

As before explained the centrifugal force of the unconnected vanes in either of the forms of my invention above described is sufficient to cause the outer edge of the vane to hug the inner surface of the sleeve (which travels in the same direction, but owing to the variation in speed of the sleeve oscillates slightly with respect to the vane), and the slight compression of air between each pair of vanes in the inner end of the slots and intercommunicating cross passages of orifices 10^b as they approach each other assists in causing the unconnected vanes to shift radially outward as the movement of the rotor permits them to do so.

Inasmuch, however, as the vanes 11 and 14 shift their positions in the rotor slot simultaneously and function as a single piston, as above explained, and the vanes 12 and 13 have like movements and function, each pair of laterally adjacent vanes may be made integral, although the difficulty of attaining accurately fitted joints with the sleeves constitutes an objection to this construction. If desired, furthermore, the vanes 11 and 14, separately formed, may be connected through a stud 30 and socket (see Fig. 4), the connection being preferably sufficiently loose-fitting to permit the vane

- 14 to seat against the inner face of the ring 8 while serving to positively cause such vane to shift with the pivoted vane 11; and the vanes 12 and 13 may be similarly connected.
- 5 If the engine is to be used as a motor, one of the flow connections, as for instance, the one through the boss 5 is connected with a source of fluid pressure, which will act upon the vane pistons successively to drive the 10 rotor and shaft 18, the fluid in front of the pistons passing through the outlet flow passages leading through the boss 5^a.
- I claim:
1. In a fluid pressure engine, a stationary 15 closed casing having within a peripheral cylindrical face and parallel end faces, a pair of similar sleeves rotatably mounted in said casing and together extending from one end face to the other, a rotor slotted on diametrical lines rotatably mounted in said casing and having a cylindrical face of lesser diameter than the inner faces of the sleeves, said rotor being arranged eccentrically of said sleeves and contacting their inner faces, a second pair of sliding vanes severally arranged diametrically opposite said pivoted vanes and each free to slidably contact the sleeve to which its diametrically opposite vane is pivoted, said casing being formed 60 with flow passages terminating in ports opening severally into the space between said rotor and pair of sleeves on opposite sides of their line of contact, and each pivoted vane together with the vane laterally adjacent to it constituting one of a pair of pistons which alternately traverse a working chamber defined by the sleeves and rotor and portions of the end faces of the casing wall intermediate said ports. 70
  2. A fluid pressure engine according to claim 1 in which said rotor is an integral body formed with two diametrically opposite radial slots in which said vane pistons are mounted. 75
  3. A fluid pressure engine according to claim 2 in which said rotor is formed with radial slots in communication with each other. 80
  4. A fluid pressure engine according to claim 2 in which each pivoted vane is loosely connected to the laterally adjacent vane.
  5. A fluid pressure engine according to claim 2 in which each pivoted vane is loosely connected to the laterally adjacent vane.
- In testimony whereof, I have subscribed my name.

MARTIN AUGUST SEAHOLM.
